POSTHOLE DIGGER

Lester E. Beck, Danville, and Lester R. Callaway,
Burlington, Iowa

Application April 15, 1947, Serial No. 741,648

2 Claims. (Cl. 255—22)

1

The present invention relates to post hole diggers of the type in which an auger is supported upon the frame of a tractor and the rotation of the auger is caused by power derived from the tractor motor. Among the objects of this invention are the provision of improved means for supporting the auger mechanism upon the frame of the tractor; the provision of improved means for adjusting the auger toward or away from the tractor; the provision of improved means for supporting and driving the auger; the provision, in a machine of the character indicated, of hydraulic means for raising and lowering the auger; and such further objects, advantages, and capabilities as will hereafter appear and as are inherent in the construction disclosed herein. Our invention further resides in the combination, construction, and arrangement of parts illustrated in the accompanying drawings and, while we have shown therein what is now regarded as the preferred embodiment of this invention, we desire the same to be understood as illustrative only and not to be interpreted in a limiting sense.

In the drawings annexed hereto and forming a part hereof,

Fig. 1 represents a side elevation of the forward portion of a tractor with the structure of our invention attached thereto;

Fig. 2 represents a front elevation of the structure shown in Fig. 1;

Fig. 3 is a plan view of a part of the auger-supporting means looking in the direction of the arrows 3—3, Fig. 2.

Fig. 4 is an enlarged detail view of the lifting and lowering connection with the upper end of the auger; and

Fig. 5 is a sectional view taken along the plane indicated by the line 5—5 in Fig. 2, showing one means for locking the auger-supporting arm against rotation.

Reference will now be made in greater detail to the annexed drawings for a more complete description of this invention. The tractor is denoted, in general, by the numeral 1 and is shown as having a pair of channels 2 secured to the side frames thereof. A post 3 is secured to one of the channels, preferably by being welded thereto so that the connection is very rigid. A cross-tie or supporting member 4 is located below the engine and secured to the tractor frame. Rising from this cross-tie is a pipe 5 which has a collar 6 rigidly connected thereto. Above the collar 6 is a collar 7 which surrounds the pipe 5 sufficiently loosely that it may turn thereabout to permit the auger and its supporting head to swing forward and back when such adjustment is desired. The collar 7 rests on the collar 6 and has a pair

2

of braces 8 secured thereto, these braces being secured to a horizontal arm 9 by bolts, as shown at 10. The arm 9 has a vertical extension 11 which fits down inside the pipe 5, as is clear from Fig. 2.

Two rods or bars 12 are secured laterally to the arm 9, as shown clearly in Fig. 3, and extend horizontally in the same direction as the arm, furnishing means for supporting a pair of sleeves 13 to which is secured the plate 14, from which depend a pair of interlocking eyes 15, serving as means for suspending the plate 16. This plate 16 has an opening 17 therein to receive the edge of the gear 18 which meshes with the pinion 19. The pinion is carried on the shaft 20 mounted in bearings on the plate 16. The shaft 20 is connected through universals 21 and 22 and the extensible shaft 23 with the shaft 24 having a pulley thereon. This pulley is connected by a belt 25 with the power take-off of the tractor and it will therefore be seen that the power unit of the tractor may be used to drive the shaft 24, shaft 23, shaft 20, gears 18 and 19, and also the hollow shaft or sleeve 26 which is mounted in suitable bearings on the plate 16 and is affixed to the bevel gear 18. Since the gear 18 is connected in driving relation with the sleeve 26, the latter will be rotated by rotation of the shaft 23. The sleeve 26 is hollow and the opening therethrough is non-circular in cross-section. The shaft or standard 27 is, likewise, non-circular in cross-section and fits slidably in the sleeve 26 which, when it is rotated, causes rotation of the shaft 27 and the auger 28, which is connected thereto in any well known manner, as by set screws 28a, as shown in Fig. 2, or by any other suitable means.

The auger 28 has a loose head 29, on the lower face of which is a bearing housing 30 in which the upper end of the auger may turn. As best shown in Fig. 4, the bearing housing 30 seats against a shoulder 101, formed by a reduced end 102 of the auger 28. The end 102 extends upwardly through the bearing housing 30 and carries a set screw collar 103 which holds the housing rotatably in place on the upper end 102 of the auger. The bearing between the housing 30 and the upper end portion of the auger 28 is shown as a plain bearing 105, but it may take the form of a ball or a roller bearing, if desired. It is to be understood that the above described means is only representative of any suitable means for effecting a raising and lowering connection with a rotatable part, such as the auger 28. If desired, this raising and lowering connection may be like that shown in U. S. Patent No. 2,400,478, issued May 21, 1946, to Lester E. Beck. A yoke 31 is secured to the head 29 by U-bolts,

as shown clearly in Figs. 1 and 2. This yoke 31 is connected rigidly to the piston rod 32 of the hydraulic or pneumatic mechanism 33 so that when air or oil is admitted through the hose 34 to the upper end of the hydraulic or pneumatic cylinder, the piston and auger will be pushed downwardly, and when air or oil is admitted through the hose 35 to the lower end of the cylinder, the auger will be raised. The controlling valve for the hydraulic mechanism is indicated at 36, and this is operated by the lever 37 within easy reach of the driver sitting on the tractor seat. Brackets 38 are secured to the plate 16 and the hydraulic mechanism and support the latter in parallel relation with respect to the auger and its shaft 27. Since these elements are parallel there will be no binding thereof when the piston rod 32 is extended or retracted.

A bracket 40 is mounted on the arm 9 and serves as supporting means for the lever 41 which is pivotally connected, as at 40a, in Fig. 3, thereto. At its opposite end, the lever 41 has a link 42 connected thereto, and this link is operatively connected to the plate 14, secured to the sleeves 13 which, as stated above, slide on the rods or bars 12. Guiding fingers 43 extend upon opposite sides of the link 42, between the rods 12. These fingers 43 are connected to a bracket 110 which is affixed, as at 111, to the plate 16, which is best shown in Fig. 2. Since the fingers 43 are spaced laterally inwardly from the interlocking eyes 15, which suspend the plate 16 and associated parts from the plate 14, the fingers 43 cooperate with the link 42 to prevent the plate 16 and associated driving mechanism from turning about a vertical axis when the auger is driven. A slidable dog 41a on the lever 41 may engage in any one of a plurality of notches 44 in a flange 45 of the bracket 40, thus holding the plate 14 in adjusted position. A second lever 46 is affixed to a lug 107, as shown in Fig. 5, which is welded to the arm extension 11 and has latching means in the form of a detent 108 and a notched sector 109 which is affixed to the upper end of the pipe 5. This latching means, which is per se conventional, serves to hold the arm 9 against inadvertent rotation relative to the supporting pipe 5.

When it is desired to drill a post hole, the auger is adjusted, as by properly manipulating the levers 41 and 46, to a position over the spot where the hole is to be formed, and then the lever 37 is operated to open the proper valve in the valve-controller 36 to cause the auger to be lowered. Now, when the clutch is thrown in to cause driving from the tractor power takeoff, the auger is rotated. In order to cause lowering of the auger, the fluid pressure is turned into the top of the cylinder 33, and this forces the shaft or piston rod 32 downwardly. The yoke 31 is connected rigidly to the lower end of the shaft 32 and it therefore goes downwardly with the shaft of the hydraulic mechanism. The yoke 31 is connected to the plate 29 of the housing 30 in which the upper end of the auger 28 is rotatably received. Thus, when the power cylinder forces the housing 30 downwardly, the auger 28 will be forced downwardly also. If the auger tends to enter the ground too quickly, the power cylinder 33 may be used to restrain and control its downward movement. If needed, a suitable bit or head may be affixed to the lower end of the shaft 27 when operating in especially hard ground. The shaft 27 slides within the driving sleeve 26, which is hollow and which, internally,

drivingly fits the shaft 27. The bearings on the plate 16 permit the sleeve 26 to be rotated, and the fingers 43 prevent the driving torque from rotating the plate 16. When the hole is dug deep enough, the valve setting in the box 36 is changed, causing the auger to be lifted.

It is of course understood that the specific description of structure set forth above may be departed from without departing from the spirit of this invention as disclosed in this specification and as defined in the appended claims.

Having now described our invention, we claim:

1. A machine for the purpose described comprising, in combination, a post for support substantially vertically upon a tractor, an extension for said post extending into it and adapted to rotate therein, an arm extending laterally from said extension, bars connected to said arm upon opposite sides thereof, a supporting element for an earth auger slidably connected to said bars, a vertically arranged plate suspended from said supporting element, a pair of shafts mounted on said plate, one arranged vertically and the other horizontally, supports on said plate for said shafts, driving gears connecting said shafts in driving relation, driving means for driving said shafts, a shaft of non-circular configuration in cross-section slidable through the vertically arranged shaft or sleeve and connected thereto to be rotated thereby, the interior of the vertically arranged shaft or sleeve being similarly non-circular in cross-section and cooperating with the first mentioned vertically arranged shaft, an earth auger connected to the shaft of non-circular cross-section for vertical motion therewith, brackets connected to and extending laterally from said plate, and a hydraulic mechanism supported by said brackets and connected to said auger to cause raising and lowering of the auger.

2. In a power driven post hole digger, substantially horizontal means for supporting an auger for substantially horizontal adjustment toward or away from a tractor, means for supporting the first means on a tractor, a plate pendulously supported edgewise from the first means and having an auger shaft supported alongside thereof for vertical movement with relation thereto, means for rotating said shaft, an auger connected to and rotating with the shaft, hydraulic means supported on said plate parallel thereto, a yoke connecting the hydraulic means and the auger, said hydraulic means being adapted to raise and lower the auger, and means for actuating the auger-supporting means toward or away from the tractor.
